SHRIMP CLEANER

William B. Sayers, Fort Worth, Tex.

Application July 19, 1954, Serial No. 31,495

Term of patent 14 years

(Cl. D11—1)

FIG. 1.

FIG. 2.

Figure 1 is a left side elevational view of a shrimp cleaner embodying my new design, and

Figure 2 is a top plan view thereof.

I claim:

The ornamental design for a shrimp cleaner, substantially as shown.
